UNITED STATES PATENT OFFICE

171,466

COVER FOR A HOT-WATER BOTTLE

Frederick P. Schur, Arlington, Va.

Application May 25, 1953, Serial No. 25,178

Term of patent 3½ years

(Cl. D83—8)

To all whom it may concern:

Be it known that I, Frederick P. Schur, a citizen of the United States, residing at Arlington, county of Arlington, State of Virginia, have invented a new, original, and ornamental Design for a Cover for a Hot-Water Bottle, of which the following is a specification, reference being had to the accompanying drawings, forming part thereof, wherein:

Figure 1 is a front elevational view of a cover for a hot-water bottle, showing my new design.

Figure 2 is a rear elevational view of the cover for a hot-water bottle of Figure 1.

Figure 3 is a side elevational view of the cover

for a hot-water bottle shown in Figures 1 and 2.

I claim:

The ornamental design for a cover for a hot-water bottle, as shown.

FREDERICK P. SCHUR.
